HAIR DRYING APPARATUS

Harvey L. Orton, Akron, Ohio

Application February 3, 1932, Serial No. 590,712

2 Claims. (Cl. 34—26)

The present invention relates to a hair drying apparatus, primarily intended for use in beauty parlors, and comprehends a construction whereby a number of persons can be attended to at the same time.

Accordingly, the invention provides a plurality of head receiving hoods into which hot air is admitted for the hair drying operation, each hood being associated with inlet and outlet pipes through which the air passes by suction.

In carrying out the invention each hood is especially constructed and equipped with a valve for regulating the flow of heated air into the hood, either at the top or from a point adjacent the bottom thereof.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

25 Figure 1 is a side elevation of the apparatus.

Figure 2 is a top plan view.

Figure 3 is a fragmentary sectional view showing one position of the valve for one of the hoods.

Figure 4 is a similar view showing another position of the valve.

30 Figure 5 is a section on line 5—5 of Figure 4.

Figure 6 is a section on line 6—6 of Figure 3.

Figure 7 is a section showing the cut off position of the valve.

35 Figure 8 is a bottom plan view thereof.

Figure 9 is a section on line 9—9 of Figure 3.

The apparatus essentially embodies a casing 10 in which the air employed is heated in any suitable manner and conveyed therefrom through a 40 sectional pipe 11. There are a plurality of these pipes all arranged in spaced horizontal relation and lead from the top of the casing 10 as illustrated. The pipes 11 successively vary in length as shown in Figure 2 thereby locating the head 45 receiving hoods supported by the outer ends of these pipes in spaced relation, so that a number of persons can be attended to at the same time. Each hood is also provided with a sectional return pipe 12, which is preferably arranged di-

50 rectly beneath its pipe 11, while all of the return pipes 12 communicate with the casing 10 through a manifold 13. The manifold is equipped with a suction fan of any suitable type indicated generally at 14 and driven from a motor 15. By virtue of this construction the heated air flowing to

each hood is drawn therefrom by suction and returned to the casing 10.

Arranged between the sections of the respective pipes 11 and 12 for each hood is a valve casting 16 in which operates a suitable valve for both regulating the flow of heated air to the particular hood, as well as to control the admission of such air thereinto either at the top or adjacent the bottom of the hood.

For this purpose each hood is of special construction, including spaced inner and outer walls 17 and 18 respectively defining an air receiving chamber 19 by the intervening space therebetween. These walls are connected at their lower ends by a wall 20 which closes the chamber at 15 this end. The wall 17 is provided with a series of openings 21 adjacent its lower edge through which communication is established between the hood proper and the chamber 19. The outer wall 18 is formed with a neck 22 arranged in spaced 20 concentric relation about the adjacent section of the pipe 11 which is connected with the inner wall at the top of the hood. The neck 22 forms part of an annular chamber 23 connected with the adjacent section of the pipe 12. By proper 25 adjustment of the valve, to be hereinafter described, heated air can be conveyed directly into the top of the hood through the pipe 11, under which circumstances the air passes downwardly through the hair and escapes through openings 20 21 into the chamber 19 from where it passes through the chamber 22 into the adjacent section of the return pipe 12. When used in this manner, the heated air is directed on the top 30 of the head of the person wearing the hood, and of course works its way to the scalp. However, the hair can be more effectively and quickly dried by intermittently directing the heated air close to the scalp and allow such air to work its way up through the hair before leaving the hood. 40 Consequently by adjusting the valve above referred to, the heated air can be conveyed to the chamber 23 through pipe 12, from where it passes into chamber 19, escaping through openings 21 45 into the hood proper adjacent the lower end thereof. As this air passes upwardly through the hair it flows from the hood through the adjacent section of pipe 11, thence through the valve into the return pipe 12.

The valve can vary in construction for the purposes above stated, but, as shown, embodies a hollow rotatable cylinder 24 mounted in the casing 16. This valve cylinder is provided adjacent its upper end with three openings 25, 26 and 27 equidistantly spaced apart in the same horizontal 50 55

plane, while it is also provided with an opening 28 adjacent its lower end. Located within the valve cylinder adjacent its lower end and at a right angle to the opening 28 is a tube 29, the latter opening at diametrically opposite sides of the valve cylinder. Arranged above this tube 29 is a curved tube 30 disposed at a right angle to the tube 29, with one end opening at one side of the valve cylinder adjacent the bottom thereof, while its other end opens at the opposite side of the cylinder adjacent the top thereof. A valve operating rod 31 depends beneath the valve casting 16 and is provided with an indicating finger 32 to indicate the position of the valve and cooperate with stop pins 33.

In practice, when the valve is positioned as illustrated in Figure 3, the opening 26 communicates with one section of the inlet pipe 11 to admit heated air into the valve cylinder, but as the tube 30 occupies a position to prohibit the passage of this air through the other section of the pipe 11, the air is forced to pass through the lower opening 28 into the adjacent section of the pipe 12. The air is thus delivered into the chamber 23 which communicates with the chamber 19 and finally enters the hood from points adjacent the bottom thereof through the openings 21. As stated, this use of the apparatus directs the heated air close to the scalp and allows the air to flow upwardly through the hair, and pass from the hood through the adjacent section of pipe 11. As shown in Figure 3, this section of the pipe communicates with the curved tube 30 which delivers the air to the return pipe 12.

35 By rotating the valve cylinder one quarter of a turn to the right, from the position it occupies in Figure 3, it assumes the position illustrated in Figure 4. In this view it will be noted that openings 25 and 27 of the valve cylinder establishes communication between the respective pipe sections 11, so that the heated air will pass through these pipe sections directly into the top of the hood. At the same time tube 29 assumes a position to establish communication between the respective sections of pipe 12 so that after the heated air escapes from the hood through openings 21 into chamber 19, it enters the return pipe and is conveyed to the casing 10 by suction. By shifting the valve cylinder to the position it occupies in Figure 9 all communication is cut off between the sections of pipes 11 and 12 respectively. The apparatus can be economically operated and easily manipulated, and by virtue of its construction a number of persons can be attended to at the same time and the hair more

effectively and quickly dried than by use of present day methods.

While it is believed that from the foregoing description the nature and advantages of the invention will be readily apparent, I desire to have it understood that I do not limit myself to what is herein illustrated or described and that such changes may be resorted to when desired as fall within the scope of what is claimed.

What is claimed is:

1. A hair drier comprising parallel hot air and cold air conduits, means for forcing air from said cold air conduit and hot air to said hot air conduit, a hair drying hood having spaced inner and outer walls, said inner wall of the hood having openings therethrough adjacent its lower edge, means connecting the top of said hood with said cold air conduit and with the latter normally communicating directly with the space between the inner and outer walls of said hood, means connecting the top of said hood with said hot air conduit and with the latter normally communicating directly with the interior of said hood, and a reversing and shut-off valve between said conduits and said hood, said valve being operable to place the cold air conduit in direct communication with the interior of the hood and simultaneously place the hot air conduit in direct communication with the space between the inner and outer walls of said hood, at will.

2. A hair drier comprising a hood having a chamber therein adapted to receive a portion of the head of a person, a first air conduit communicating with said chamber in said hood, a second air conduit communicating with said chamber in said hood, air heating means, air moving means, means to conduct air to said air moving means, means to conduct air away from said air moving means, adjustable means between said hood and said air moving means which in one position establishes communication between said first air conduit and said means to conduct air to said moving means and also between said second air conduit and said means to conduct air away from said air moving means and which in another position establishes communication between said first air conduit and said means to conduct air away from said air moving means and also between said second air conduit and said means to conduct air to said air moving means, so that said first and second conduits act alternately as incoming and exhaust air conduits and whereby the direction of flow of air through said hood is reversed.

HARVEY L. ORTON.
